UNITED STATES PATENT OFFICE.

GEORGE W. HAMILTON, OF PHILADELPHIA, PENNSYLVANIA, ASSIGNOR TO BURNHAM, WILLIAMS & COMPANY, OF PHILADELPHIA, PENNSYLVANIA, A FIRM.

TROLLEY-POLE.

SPECIFICATION forming part of Letters Patent No. 730,116, dated June 2, 1903.

Application filed March 23, 1903. Serial No. 149,070. (No model.)

To all whom it may concern:

Be it known that I, GEORGE W. HAMILTON, a subject of the King of Great Britain and Ireland, (but having declared my intention of becoming a citizen of the United States,) residing in Philadelphia, Pennsylvania, have invented certain Improvements in Trolley-Poles, of which the following is a specification.

10 The main object of my invention is to construct a trolley-pole which will have an extended movement with a limited amount of expansion and contraction of the controlling-spring.

15 A further object of the invention is to reduce the wear of the trolley-wheel.

These objects I attain in the following manner, reference being had to the accompanying drawings, in which—

20 Figure 1 is a side view showing the improved pole raised to bear against a high wire. Fig. 2 is a view showing the pole lowered to bear against a low wire. Fig. 3 is an enlarged sectional plan view of the spring and its connections. Fig. 4 is a view showing the application of a compression-spring in place of the tension-spring illustrated in Fig. 1, and Fig. 5 is a view showing the pole provided with two trolley-wheels.

25 A is the body of the car, on which is secured a bracket *a*. Arms *B B* are pivoted at *b b* to the bracket *a*. In the present instance these arms have toothed segments *b'*, which mesh with each other, so that the arms will move in unison.

30 Pivoted to the upper ends of the arms *B B* at *c* are arms *C C*, connected together at their upper ends in the present instance by a pivot-pin *d* of the trolley-wheel *D*. This trolley-wheel can be shaped as desired. The four arms form one section of a lazy-tongs, so that the trolley-wheel can have an extended movement from and toward the car-body to accommodate different heights of supply-wire.

35 This arrangement is a common construction and is known as the "scissors" type of trolley-pole; but the devices for keeping the trolley-wheel against the wire as heretofore manufactured have been such that it necessitated a very long movement of the spring,

which is highly objectionable for several reasons.

By my invention I am enabled to use a spring having a very slight movement, and I can use the spring either under tension or 55 compression.

Secured to the arms *B B* at *e e* are links *E E*, and secured to the arms *C C* at *f f* are links *F F*. These links are connected together by pivot-pins *i i*, and extending from 60 one pivot *i* to the other is a spring *G*. One end of the spring in the present instance is hooked around the head *i'* of one pin, and the opposite end of the spring is attached to a threaded bolt *g*, which extends through an 65 opening in the head *i''* of the other pin *i*, and on this bolt are adjusting-nuts *g'*, by which the spring can be adjusted.

In Figs. 1 and 2 the links are of such a length and are in such a position on the arms 70 that the spring is under tension, and it will be noticed that there is a very slight movement of the spring from the position shown in Fig. 1 to the position shown in Fig. 2; but there is sufficient movement to extend the 75 pole without undue pressure, and yet when the pole is extended to a certain height the movement is limited.

I preferably mount the pivots *e* and *f* on sleeves which may be adjusted on their arms, 80 and these sleeves can be secured after adjustment by set-screws or other fastening devices.

In Fig. 4 I have so proportioned the links that a compression-spring must be used, as 85 the distance apart of the pivot-points *i i* is greater when the pole is in its raised position than when it is in the depressed position. The spring *G'* in this instance is mounted between two heads *h h*, and extending from 90 each head is a tube carrying a telescopic section to hold the spring in line.

In order to enable high amperage currents to be collected without the use of two poles, I mount two trolley-wheels *D' D'* on a bracket 95 *D''*, carried by the arms *C C*, as shown in Fig. 5.

It will be seen that by the construction above set forth I obtain a maximum range of trolley with a minimum movement of spring, 100

and the pole does not jump above the maximum height of wire when it leaves the same, and, furthermore, I reduce the wear on the trolley-wheel due to the even pressure on the 5 wire.

The device is simple in construction, only one spring being necessary, and this spring may be either in tension or compression, according to the arrangement of the links.

10 I claim as my invention—

1. The combination in a trolley-pole, of the two sets of arms pivoted together, two sets of links connected to the arms, and a spring connecting the two sets of links, substantially as described.

2. The combination of the two lower arms of a trolley-pole, two upper arms connected to the lower arms, the upper ends of the arms being connected together, two sets of links, 20 one set being connected to the upper arms and the other set being connected to the lower arms, the links of the upper arms being connected to the links of the lower arms, a spring connecting the two sets of links, and a trolley-wheel carried by the upper arms, substantially as described.

3. The combination in a trolley-pole, of two sets of arms pivoted together, two sets of links connected to the arms, and a spring connecting the links on one side to those on the opposite side, with means for adjusting the 30 spring, substantially as described.

4. The combination in a trolley-pole, of two sets of arms pivoted together, two sets of links

connected to the arms, a spring connecting 35 the links on one side to those on the opposite side, a bracket pivoted to the arms, and two trolley-wheels mounted on the bracket, substantially as described.

5. The combination in a trolley-pole, of two 40 lower arms, two upper arms pivoted to the lower arms, a trolley-wheel carried by the upper arms, two sets of links, one set being connected to the upper arms and the other set connected to the lower arms, the upper 45 links being pivoted to the lower links, and a spring extending from the pivot on one side to the pivot on the other side, substantially as described.

6. The combination in a trolley-pole, of two 50 lower arms, two upper arms pivoted to the lower arms, a trolley-wheel carried by the upper arms, two sets of links, one set being connected to the upper arms and the other set connected to the lower arms, the upper 55 links being pivoted to the lower links, and a spring extending from the pivot on one side to the pivot on the other side, said links being adjustable on the arms, substantially as and for the purpose set forth.

60

In testimony whereof I have signed my name to this specification in the presence of two subscribing witnesses.

GEORGE W. HAMILTON.
